UNITED STATES PATENT OFFICE.

GEORGE W. VINSON, OF HAZLEWOOD, KENTUCKY, ASSIGNOR OF ONE-HALF
TO J. EDUARD MARTIN, OF HAZLEWOOD, KENTUCKY.

CORNER-IRON FOR VEHICLE-BODIES.

SPECIFICATION forming part of Letters Patent No. 697,298, dated April 8, 1902.

Application filed December 20, 1901. Serial No. 36,722. (No model.)

To all whom it may concern:

Be it known that I, GEORGE W. VINSON, of Hazlewood, in the county of Ballard and State of Kentucky, have invented certain new and 5 useful Improvements in Corner-Irons for Vehicle-Bodies, of which the following is a specification.

The object of this invention is to provide a corner-iron for securing the abutting ends of 10 the side boards of a vehicle-body and at the same time so form the iron as to provide additional support for the said side boards and by reason of its conformation and a vertically-disposed securing-bolt provide means for fastening the ends of the framing of the body, 15 all as will be hereinafter fully described.

I am aware that a one-piece corner-iron is not, broadly, new and do not therefore desire to be understood as claiming, broadly, any 20 such construction. I do think, however, the special corner-iron invented by me is new and that it affords a more rigid, simple, and effective fastening than possible with such irons as they are now constructed.

25 Particular attention is called to the fact that with my special corner-iron one bolt at each corner forms the sole means for fastening adjoining ends of the framing of the body and that it is the only fastening connecting the 30 framing with the corner-irons, save one or more screws passed horizontally through a downward extension of one side of the iron and the lower end of the extension bent horizontally to pass under the side boards of the 35 body to support them and obviate strain on the devices connecting the sides with the corner-irons. With such construction increased rigidity at the corners is provided and by simple, effective, and improved means.

40 Having thus briefly stated the use and advantages in such an iron as invented by me, I will now proceed to describe it in detail, reference being had to the accompanying drawings, which form a part of this specification, 45 and in which—

Figure 1 is a sectional end elevation of the body. Fig. 2 is a detail perspective view of one of the corner-irons. Fig. 3 is a detail perspective view of a somewhat different form of 50 corner-iron from that shown in Fig. 2. Fig. 4 is a detail vertical section on about line 4 4

of Fig. 1, and Fig. 5 is a detail vertical section drawn through the head and the adjacent portions of the dashboard and end member of the body.

55 My corner-iron may be made after any approved method, such as casting, stamping with dies, or otherwise fashioned. It consists of an angular or other shape upright body A, formed by side members A' A². The member A' projects downward beyond the member A², as shown at A³, and is at its lower end provided with an outwardly-projecting shelf B. This shelf is designed as a support for the side boards of the body, as will appear farther on.

60 The two members A' A² are braced by an integral horizontally-disposed base-plate E, located at the lower end of the member A². The plate E is provided with a vertical hole 65 to receive a fastening-bolt, as shown and hereinafter described.

70 As a means for supporting the dashboard the member A' of the body portion is extended and formed into a head F and the head perforated to receive a bolt passing through the dash.

75 It is obvious that the members A' A² should have bolt-holes, as at G, for receiving bolts, screws, or other fastening of the side boards, 80 and the projection A³ of the member A' is also perforated to receive screws entering transversely into the framework of the body, as shown.

85 When the corner-irons are in place, the base-plate E rests upon the framework and is fastened by a bolt H, passing through it and the lapped ends of the frame.

90 It is understood that all the corner-irons are fastened as just described. The bolts H of the forward corner-irons, however, are extended above the base-plate E for supporting a foot-rest I, which latter has its ends perforated to receive the said bolts and be fastened by a nut at the upper end of the bolt.

95 With my special corner-irons it will be seen that having all the parts in the make-up of a vehicle-body in proper shape they can be sold in a knockdown condition and be assembled and secured as desired in a short space of time by unskilled labor.

100 Owing to close competition in the trade, the

element of time expended in manufacturing vehicle-bodies and placing the finished article on sale has become an important consideration. An article of this type, however, 5 must have merit, and with that idea in view I have devised the hereinbefore - described corner-iron so formed that with all the parts in the make-up of a vehicle-body in proper shape the same can be assembled and secured 10 by unskilled labor. As before stated, I am aware that a one-piece corner-iron is not new; but my special form of iron is new and will be appreciated by those skilled in the art.

Having thus fully described my invention, 15 what I claim as new, and desire to secure by Letters Patent, is—

1. A corner-iron consisting of a body portion one member of which terminates at a sub-

stantially right-angle base-plate as set forth, and the other member extends below the base-plate and the member terminating at the base-plate and having its lower end bent outwardly forming a shelf substantially as shown and for the purpose set forth. 20

2. A one-piece corner-iron consisting of a 25 body portion, a base-plate integral therewith, and a downward extension from one member of the body portion having a shelf at its lower end, the other member of the body portion being constructed with an upwardly-projecting head forming a support substantially as 30 and for the purpose set forth.

GEORGE W. VINSON.
